Primary Examiner — Sandra L Morris(74) *Attorney, Agent, or Firm* — Novick, Kim & Lee, PLLC; Jae Youn Kim(57) **CLAIM**

I claim, the ornamental design for a package wrapper, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a package wrapper, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

Two registered trademarks are shown in the drawings. The design mark shown on top left of the front view (transliteration: DAERIMSUN) is a registered Korean trademark by Sajo Daerim Corporation. The design mark shown on top right of the front view (SAJO) is a registered U.S. and Korean trademark owned by Sajo Industries Co., Ltd. and Sajo Seafood Co., Ltd.
